103,302

DESIGN FOR A COMBINED COMB AND HOOK

William N. Brady, Piermont, N. Y., assignor to
American Hard Rubber Company, New York,
N. Y., a corporation of New York

Application November 25, 1936, Serial No. 66,134

Term of patent 14 years

To all whom it may concern:

Be it known, that I, William N. Brady, a citizen of the United States and a resident of Piermont, in the county of Rockland and State of New York, have invented a new, original, and ornamental Design for a Combined Comb and Hook, of which the following is a specification, reference being had to the accompanying drawing, forming a part thereof and in which:—

The figure is a side elevation of a combined comb and hook embodying my new design.

The reverse side of the comb is substantially of the same appearance as the side shown.

The characteristic feature of my design resides in the combined comb and hook, the latter tapering gradually away from the comb portion towards the free end, as shown.

I claim:

The ornamental design for a combined comb and hook, as shown and described.

WILLIAM N. BRADY.
